UNITED STATES PATENT OFFICE.

GEORGE F. WATTS, OF BOSTON, MASSACHUSETTS.

DERRICK.

1,423,376.

Specification of Letters Patent. Patented July 18, 1922.

Application filed July 13, 1921. Serial No. 484,458.

To all whom it may concern:

Be it known that I, GEORGE F. WATTS, a citizen of the United States, residing at the city of Boston, county of Suffolk, State of Massachusetts, have invented new and useful Improvements in Derricks, of which the following is a specification.

This invention relates to an improvement in derricks, and more particularly to 10 the foot block and its application to and use with the mast.

The mast employed in structural work is generally of great height and of considerable weight, and it has been found difficult 15 to rotate the mast for the purpose of changing its position, as this is generally performed manually, due to the great amount of friction which is created at the base of the mast or the foot block, and the excessive weight of the mast and the load which may be imposed on the mast and boom. It has been found by actual experience and use of the present invention that this difficulty may be overcome, and the shifting or rotating of the 20 mast may be accomplished with comparative ease and less man power than heretofore.

A feature in the construction of the foot block, is to eliminate friction and to provide a support or base for the mast where- 30 by the pressure on the ball race is evenly distributed regardless of the position of the mast, whether the mast is perpendicular with respect to the foot block, or at an angle thereto.

The foot block consists of a base plate and a mast step, and the mast step is provided with a hub which rotatably fits an opening in the base plate thereby affording a connection between the two members. Inter- 40 posed between the two members are ball bearings traveling in suitable ball races on the respective members.

Considerable stress is imposed on the foot block, as the boom which is carried by the 45 mast is elevated, and the horizontal thrust of the boom transmitted to the mast, is taken care of by the hub of the mast step entering into the base plate. It will therefore be recognized that the pressure exerted 50 on the block by the mast from either a perpendicular or angular direction is taken care of by the ball bearings, and the stress transmitted in a horizontal direction by the boom is cared for by the hub on the mast step so 55 that with all the pressure and strain imposed on the foot block it is constructed to

withstand such conditions without binding or the creation of friction and permitting the mast to function properly.

The invention consists of certain novel 60 features of construction and combination of parts which will be hereinafter described and pointed out in the claims.

In the accompanying drawings:

Figure 1 is a view in elevation showing 65 the invention;

Figure 2 is a detail view elevation and partly in section showing the mast and boom supported on the foot block;

Figure 3 is a detail view in vertical sec- 70 tion of the mast and foot block;

Figure 4 is a horizontal sectional view on line 4—4 of Figure 2;

Figure 5 is a perspective view of the lower 75 end of the boom;

Figure 6 is a transverse vertical sectional view on line 6—6 of Figure 2, showing the manner of attaching the boom to the mast;

Figure 7 is a detail view in side elevation 80 of the lower terminal of the mast; and

Figure 8 is a perspective view of the lock- 85 ing plate employed for fastening the boom pin to the mast plate.

Referring to the drawings A represents a skeleton mast and B the boom. These ele- 85 ments, the mast and boom, are preferably for the most part of standard construction.

Suitable beams 1, 1 are bolted together and interposed between these beams are sheaves 2, 2, journaled on the shaft 3 extending 90 through the beams 1. A plate 4 is mounted on the shaft 3 for supporting the two sheaves 2, and is held against lateral movement by means of bolts or rods 5.

The foot-block is mounted upon the beams 95 1 and consists of a base plate 6 provided with a plurality of holes around the peripheral edge through which are received bolts 7, 7, which pass through the beams 1 for attaching the base plate thereto. Mounted upon the base plate is the mast step 8 having a hollow hub member 9 which extends into an opening 10 formed in the base-plate 6. A suitable bushing 11 encircles the hub for forming a wearing surface between the hub 105 and base plate. A ring 12 is connected to the lower end of the hub 9 and engages the under surface of the base plate 6 for connecting the two members together. The upper face of the base plate 6 and the lower face of the 110 mast step 8 is each provided with a ball race 13, and 14, respectively, in which are re-

ceived a plurality of ball bearings 15 for forming an anti-friction bearing between the two members. The upper face of the base plate 6 is also preferably hollowed out as 5 at 16 for forming a lubricant receptacle whereby the balls will be properly lubricated.

The mast step 8 is provided on its upper surface with a plurality of vertical ribs 17, 10 17, a pair of ribs being located on each side of the center of the mast step, and each pair being in parallel relation. The space between the ribs of each pair being of like distances and depths. The central 15 ribs are connected together by webs 18 while the outer ribs are provided with vertical webs 19 extending from the upper face of the mast step, whereby the several ribs are properly braced and strengthened.

20 On two opposite sides of the mast A are attached plates 20, 20 by means of rivets 21. These plates extend beyond the lower end of the mast A and have attached thereto reinforcing plates 22 and 23. These plates 20 are provided with holes or elongated slots 24, 25 as clearly shown in Figure 7. The plates 20 are received between the parallel ribs 17 and a slot 24 in each plate 20 is adapted to register with holes 25 in the parallel ribs 17.

30 A pin 26 passes through each pair of parallel ribs 17 and through the slots 24 of the plates 20 for attaching plate 20 between a pair of the ribs 17 and forming a pivotal connection for the mast A with the foot block and mast step 8. The pins 26 are provided with transverse slots 27 in which an edge of a locking plate 28 is received. These locking plates 28 are attached by suitable screw bolts 29 to the outer faces of the 40 outermost ribs 17 for holding the pins against longitudinal movement.

The connection of the mast A and the mast step 8 by the plates 20 is such that a suitable clearance is formed between the ribs 17, and 45 between the upper face of the mast step 8 and the plates 20. This clearance together with the slotted pin connection between the plates 20 and ribs 17, allows the mast to deviate from a vertical position without binding the ball race and the pressure on the ball race is always evenly distributed regardless of the position assumed by the mast.

This construction makes provision for carrying the cables which operate the boom 55 through the skeleton mast, the hollow hub 9 of the mast step 8 and thence over the sheaves 2.

The lower end of the boom B, more particularly shown in Figure 5, is reinforced by 60 means of external plates 30 and angle iron partition plates 31, 31. Extending through suitable openings formed in the end of the boom plates 30 and partition plates 31 is a pin 32. Cotter pins 33 extend through the 65 pin 32 on each side of the partition plates 31

for locking the pin against longitudinal movement. Plates 20 of the mast A are provided with lateral extensions 34 and these extensions are provided at their ends with open end slots 35 into which the ends 70 of the pin 32 are received. The extensions 34 are preferably reinforced by filler plates 36 and angle iron plates 37. The ends of the filler plates 36 and angle iron plates 37 being slotted to conform to the slot in the 75 lateral extension. A locking plate 39 provided with a hole 40 is employed for securely attaching the boom to the mast. The hole 40 of the plates 39 receives the ends of the pin 32 and the plates 39 are bolted to the 80 lateral extensions 34 whereby the boom is securely held in place.

The slots 35 in the lateral extensions 34 of the mast afford a ready means of attaching the boom B to the mast as the pin 32 of the 85 boom can be readily inserted in the slots 35 and then by means of the locking plates the boom pin 32 is held to the lateral extensions to prevent it from becoming disengaged therefrom. This connection eliminates the 90 difficulty usually encountered in inserting a pin through openings formed in the mast and boom in attaching the boom to the mast.

The hub 9 of the mast step 8 coaxing with the opening in the base plate 6 receives the 95 thrust transmitted to the mast by the boom B, and prevents the possibility of the mast step being forced or caused to ride over the ball bearings, which would occur if the hub was not provided on account of the heavy 100 load carried by the boom. The greatest stress imparted to the mast by the boom being when the boom is in a horizontal plane.

The mast A is preferably located centrally 105 of the mast step 8 so that the pressure of the mast will be exerted upon the ball bearings evenly. It is essential that the mast be pivoted to the mast step because under different conditions of use of the boom the 110 mast will be caused to move one way or another, and as a result the pressure of the mast will be imparted to the mast step and ball bearings, yet by the central location of the mast, this pressure will be evenly distributed among the several balls of the anti-friction bearing, and the thrust of the boom 115 will always be cared for by the hub 9.

The arrangement of the several parts of the derrick has been adopted for the purpose 120 of taking care of the pressures on the foot block by the mast and the stress is imparted thereto by the boom so that it is possible to rotate and operate the derrick with the greatest ease.

It has been demonstrated with this construction that the mast may be rotated under the most trying conditions by one man, whereas, at present with most of the derricks in use, it is either necessary to employ 130

several men to rotate the mast or to employ a block and tackle.

Having described my invention what I claim as new and desire to secure by Letters 5 Patent is:

1. The combination of a foot-block consisting of a base plate and a mast step, anti-friction bearings interposed between the base plate and mast step, and a mast pivotally connected to the mast step and centrally located thereon, whereby the pressure exerted on the foot block by the mast regardless of its angle is equally distributed on the base plate by said anti-friction means.
- 15 2. The combination of a foot block including a base plate having a central opening and a mast step rotatably mounted thereon having a hub loosely fitted in the opening of the base plate, anti-friction bearings interposed between the base plate and mast step, and a mast pivotally connected to the mast step and centrally located thereon, whereby the pressure exerted on the foot block by the mast regardless of its angle is 25 equally distributed on the base plate by said anti-friction means.
3. The combination of a mast, a foot block, said foot block consisting of a base plate and a mast step, the base plate being provided with a central opening, a hollow hub on the mast step extending into the opening of the base plate, anti-friction bearings interposed between the base plate and

35 mast step and plates carried by the mast and having pivotal connection with the mast step.

4. The combination of a mast having openings in an end thereof, a foot block including a base plate having a central opening, and a mast step rotatably mounted on 40 the base plate provided with a hub extending into the opening of the base plate, anti-friction bearings interposed between the base plate and mast step, ribs on the mast step, and means passing through the ribs 45 and the openings of the mast for pivotally connecting the mast to the mast step.

5. The combination of a mast having plates extending below the end thereof, said plates having slots therein, a base plate, a 50 mast step rotatably mounted thereon, ribs on the mast step, a rib being located on each side of a mast plate, and means for pivotally connecting the mast plates to a pair of ribs.

6. In a derrick the combination of a mast, 55 a foot block, including a base plate and a mast step rotatably mounted thereon, plates carried by the mast having pivotal connection with the mast step, said plates being provided with lateral extensions, which extensions are provided with slots, and a boom having a pin received in said slots of the lateral extensions for connecting the boom thereto.

GEORGE F. WATTS.
